[57] CLAIM

The ornamental design for a combined end hood mounting and terminal housing for the shaft of a roller awning, as shown.

DESCRIPTION

FIG. 1 is a front, top and right side perspective view of a combined end hood mounting and terminal housing for the shaft of a roller awning showing my new design; FIG. 2 is a side elevational view thereof;

FIG. 3 is a front elevational view, the rear elevational view being a mirror image except for the obvious absence of the positioning arm and its circular grip shown in FIGS. 1-3.

The broken line showing of attachment of the ring end section to an awning roller in FIGS. 1, 3, 4 is for illustrative purposes only and forms no part of the claimed design.
